UNITED STATES PATENT OFFICE

162,143

ELECTRICALLY OPERATED WINDOW VENTILATOR

Herbert P. Fields and Bruno Kucinski,
Chicago, Ill.

Application June 22, 1950, Serial No. 10,692

Term of patent 14 years

(Cl. D62—4)

To all whom it may concern:

Be it known that we, Herbert P. Fields and Bruno Kucinski, citizens of the United States, residing at Chicago, in the county of Cook, and State of Illinois, have invented a new, original, and ornamental Design for an Electrically Operated Window Ventilator, of which the following is a specification, reference being had to the accompanying drawing, forming part thereof, wherein:

Figure 1 is a front elevation of an electrically operated window ventilator showing our new design;

Fig. 2 is a rear elevation thereof;

Fig. 3 is a top plan view thereof; and

Fig. 4 is an end elevation thereof.

We claim:

The ornamental design for an electrically operated window ventilator, as shown.

HERBERT P. FIELDS.
BRUNO KUCINSKI.
